UNITED STATES PATENT OFFICE.

JOSIAH W. ARCHBALD, OF PORTO RICO, WEST INDIES, ASSIGNOR TO
HORACE SOUTHMAYD.

IMPROVEMENT IN SUGAR-DRAINING MACHINES.

Specification forming part of Letters Patent No. 9,560, dated January 25, 1853.

To all whom it may concern:

Be it known that I, JOSIAH W. ARCHBALD, of the Island of Porto Rico, in the West Indies, and a subject of the King of Spain, have invented a new and useful Improvement connected with Centrifugal Sugar-Machines; and I hereby declare that the following is a full, clear, and exact description of the same, reference being had to the annexed drawings, forming part of this specification, in which—

Figure 1 is a plan view. Fig. 2 is a vertical sectional elevation. Fig. 3 is a vertical section of the loose bag when placed in the machine. Fig. 4 is a view of the loose bag.

The same letters of reference indicate like parts.

To enable others skilled in the art to make and use my invention, I will proceed to describe the nature, construction, and operation of the same.

The nature of my invention consists in employing a loose bag of cotton, linen, hair-cloth, or any such fibrous or flexible material, in combination with the "American centrifugal refining sugar-machine," by placing the said bag in said machine loosely, or securing it by loops, with the sugar to be operated upon inside of it to keep the sugar from attaching itself to the wire-gauze or perforated cylinder when the machine is in motion, and whereby the whole of the sugar, when refined, can be at once lifted out of the machine by lifting out the said bag containing the sugar, so that another bag full of sugar can be placed in the machine to go through the same operation, thus saving the loss of time usually entailed by scraping off the sugar from the wire-gauze or sides of the rotating cylinder, and whereby one bag can be emptied and cleaned when another is being employed, so as to keep the machine in active operation much longer in a certain number of hours than is possible by the common modes of working such machines.

A is an outside cylinder, made of sheet or plate metal. It has a bottom, *a*, and a spout, *b*, on it. This cylinder is stationary and fixed. It has an opening through the center of its bottom for the driving-shaft *c* to pass through.

B is an interior cylinder. Its sides are made of perforated copper plates or of wire-gauze; but its bottom *d* is made of sheet or plate metal, and it has a broad metal flange at its

top, and is strengthened by metal rods *r*. The bottom of this interior wire-gauze cylinder is made of a conical form at the center, the cone being hollow on the outside, to admit and receive the driving shaft *c*, which passes into a collar, *g*, firmly securing the said cylinder to said shaft, so that when said shaft is revolved it will give the said cylinder a rapid rotary motion.

The parts of said machine so described are not new. They are old, and need not be further described. Such machines are in common use for refining sugar.

The sugar to be operated upon is mixed with a certain quantity of molasses and placed inside of said perforated cylinder, which then receives a rapid rotary motion, when, by the centrifugal action of the force thus communicated to the machine, the sugar is thrown upon the sides of the cylinder, the molasses and other moisture in the sugar pass through the wire-gauze and out of the machine by the spout *b*, and in a short time the sugar, which was put into the machine in a dark-brown wet state, is found in a nearly dry state, greatly purified and adhering to the inside of the wire-gauze cylinder. To empty or discharge the cylinder of its sugar, the said sugar has to be scraped off the sides of the perforated cylinder. This is a laborious and tiresome part of the process of refining sugar, involving a great deal of time and toil, and consequent loss of a machine's operation; and, besides, the wire-gauze has to be washed frequently, and this also involves a further loss of time by the stoppage of the machine for such a purpose. I obviate this loss of time of the machine's active daily operations, also the scraping off the sugar and washing the perforated cylinder, by the employment of a loose bag to contain and retain the sugar in the machine, and for discharging said sugar rapidly from the machine. This bag *L* is made of coarse cotton, linen, grass-cloth, or any fibrous or like flexible materials, and is of a form like that represented in Fig. 4. This bag must be made loose and wide, so as to set in the cylinder, and its bottom set on and be retained by the central cone of the cylinder, as shown in Fig. 2. This bag must be of such a quality of mesh as to allow the molasses, when the machine is revolving, to pass freely through or between the threads

which compose its warp and weft. The sugar to be acted upon in the machine is prepared for that purpose, and is placed in the bag, then simply placed in the machine; or the sugar may be poured into the bag after it is placed in the cylinder and the cylinder B set in rapid motion. This bag then assumes the position represented in Fig. 2. The molasses is thrown through its meshes and passes through the perforated sides and out of the spout *b*, and when the sugar is sufficiently depurated the machine is stopped, the lips of the bag are brought close together, its mouth closed, the bag lifted out in a moment, and with it the whole sugar, which has been refined. Another bag is at hand with sugar in it, as before described. It is placed in the machine, which is again set in motion, while the former bag is being emptied, and thus time, labor, &c., are saved by this simple improvement.

By this improvement the impurities which usually fill up the interstices or perforations in the sides of the machine, and which cause a loss of the machine's operation, by having to be frequently washed, are retained in the meshes of the loose bag *L*, which bag can be speedily rinsed in water and cleansed, while another bag is in the machine, thus enabling the machine to be run during the time which is now occupied in washing it.

The size of the bag is proportioned to the size of the machine. It must be of a size and form to retain the sugar and spread out in the machine, and be about large enough to come up to or over the top flange, *f*, but quite loose, so that its mouth can be easily closed and be lifted up and out with the sugar in it. Any person can make such a bag from this description. This bag could not be used in a centrifugal machine driven with a central top vertical shaft. It can only be used in the "American centrifugal sugar-machine," which is open and free inside, and is driven by a shaft from the bottom, as shown in Fig. 2. The bag is not permanently secured by clamp or otherwise to the rotating cylinder; hence it is so easy of management and so convenient and useful. Besides saving a great deal of labor by my improvement—this loose bag *L*—I am

enabled to save in the running of one centrifugal machine about two hours out of the ten, which amounts to one day of twelve hours for a single machine in a week. Sugar can also be steamed or washed with this bag in the machine. Its value to sugar-refiners is of great importance.

Pins or hooks may be secured on the cylinder, and loops or eyes made in the bag to loop or hook on the said pins or hooks; but the bag must be so loosely attached to the cylinder as to be rapidly placed in and lifted out from it. A loose bag, however, operates perfectly, and I prefer it as the most simple arrangement; but the hooks, &c., and loops may be employed, if desired, as a modification of the principle.

I am aware that a bag of fibrous material has been employed in combination with a top spindle sugar-machine in London; but it was only employed for discharging the contents of the cylinder by being secured to a nut on a central screw-shaft and permanently clamped to the edge or rim of the cylinder. The bag was run up by the screw, and it simply threw out the sugar over the sides of the machine. My bag could not be employed in such a machine at all, and my invention is entirely different, as my bag is loose, is not permanently attached to the machine, and accomplishes other objects, as heretofore set forth.

Having thus described the nature and operation of my invention, what I claim as new, and desire to secure by Letters Patent of the United States, is—

The employment of a fibrous or flexible bag made of cotton, linen, hair-cloth, or any other substance placed loosely or secured by loops, as described, in a centrifugal depurating sugar-machine inside of the wire-gauze cylinder and containing the sugar, said bag not being permanently attached to the machine by any screw or clamp, &c., but to be freely placed in and then lifted out of the machine entirely when the sugar is depurated, for the purposes set forth.

J. W. ARCHBALD.
